UNITED STATES PATENT OFFICE.

HARRY L. HOFFMAN, OF NEW YORK, N. Y., ASSIGNOR TO RICHARD E. THIBAUT, INC., OF NEW YORK, N. Y., A CORPORATION OF NEW YORK.

DESIGN FOR A WALL-PAPER PANEL OR THE LIKE.

Application filed April 27, 1928. Serial No. 26,473. Term of patent 7 years.

To all whom it may concern:

Be it known that I, HARRY L. HOFFMAN, a citizen of the United States, and a resident of the city of New York, borough of Manhattan, in the county of New York, and State of New York, have invented the new, original and ornamental Design for a Wall-Paper Panel or the Like, of which the following is a specification, reference being had to the accompanying drawing, forming a part thereof.

In the accompanying drawings—
The figure is a view in elevation of a wall paper panel, showing my new design.

I claim:
The ornamental design for a wall paper panel or the like, as shown.

Signed at N. Y., in the county of N. Y., and State of N. Y., this 26 day of April, A. D. 1928.

HARRY L. HOFFMAN.
